INCANDESCENT ELECTRIC LAMP FOR
SERIES SERVICE

Clair Michael Rively, Bloomfield, and Kenneth G. Crocker, East Orange, N. J., assignors to Westinghouse Electric Corporation, East Pittsburgh, Pa., a corporation of Pennsylvania

Application June 21, 1947, Serial No. 756,228

8 Claims. (Cl. 176—16)

1

This invention relates to incandescent electric lamps particularly adapted for series service, and more especially to a lamp with a device associated with its leads for continuing an electric circuit therethrough in case the filament fails during service.

The principal object of our invention, generally considered, is to provide an incandescent electric lamp with circuit-maintaining means associated with its leads, whereby if the filament breaks while energized during series operation with other lamps, the circuit is maintained without interruption, thereby preventing the associated lamps from being unintentionally extinguished.

Another object of our invention is to provide a cut-out feature for use with 30 volt series lamps, whereby such a lamp may be used in a 20-lamp, 600 volt, D. C. circuit, and maintain continuity of the circuit even upon failure of its filament.

A further object of our invention is to provide for spacing the lead wires of a series-service incandescent electric lamp a very short distance, say from .0005" to .003", as by means of a perforated insulator, whereby upon failure during operation of the lamp filament, the circuit through lamps in series therewith is maintained by arcing through the insulator.

A still further object of our invention is to provide for spacing inner portions of leads of an incandescent electric lamp by means of foraminous insulating material, such as a small piece of glass ribbon woven from thread .0015" in diameter and held in place by a metal strap properly staked, whereby upon failure of filament, arcing through the interstices occurs and maintains the operation of lamps which may be in series therewith.

Other objects and advantages of the invention will become apparent as the description proceeds.

Referring to the scale drawing:

Figure 1 is an elevational view, full size in the drawing accompanying this application, with parts broken away, of an incandescent electric lamp embodying our invention.

Figure 2 is an enlarged elevational view, with parts in section, of a portion of the mount of such a lamp.

Figure 3 is a further-enlarged horizontal sectional view on the line III—III of Figure 2 in the direction of the arrows.

Figure 4 is an elevational view of a piece of woven glass ribbon which may be employed for spacing the leads of a lamp embodying our invention.

2

Figure 5 is a perspective view of a metal strap bent preparatory to holding the glass ribbon in place.

Figure 6 is a view corresponding to Figure 3, but showing a modification.

Figure 7 is another view corresponding to Figure 3, but showing another modification.

Figure 8 is a diagrammatic view of several lamps embodying our invention and arranged for series operation.

When ordinary incandescent electric lamps are burned in series, the whole string is extinguished upon failure of one of the filaments. When such lamps are designed for street rail-
15 way series service using, for example, 30 volt lamps operated 20 in a string with available potential of 600 volts, it has been the practice to place a small piece of oxidized aluminum plate between adjacent portions of the filament leads, and hold said plate in place by means of a ceramic insulator. Upon failure of the filament, and when the entire 600 volts of the line is available at such a point, an arc occurs breaking down the oxide coating on the aluminum plate and main-
20 taining the circuit through other lamps in the series. However, such an arrangement is not entirely satisfactory because it is somewhat uncertain and comparatively expensive.

In accordance with our invention, we have replaced the oxidized aluminum separator by a foraminous insulating sheet or film and the supporting relatively expensive ceramic holder by a relatively cheap small metal strap thereby saving a large proportion of expense of such a cut-out device, while at the same time improving the operation of the lamps having such cut-out.

Referring to the drawing in detail, and first considering the embodiment illustrated in Figures 1 to 5, inclusive, there is shown a lamp 11 provided with a translucent or transparent vitreous or glass envelope 12, to which is sealed a flare tube 13 having leads 14 and 15. The outer end or flaring portion 16 of the tube 13 is sealed to the neck or small portion of the bulb 12. Dis-
45 posed between the leads and outwardly of the press 17 is an exhaust tube 18, communicating with the interior of the envelope through opening 19 in the press 17.

Secured to the inner ends of the leads 14 and 15 is an incandescent filament 21, which in the present embodiment is shown as coiled. Portions of the leads between the press 17 and the filament 21 are disposed parallel and close together, as indicated at 22. Between said parallel 55 closely-spaced lead portions is disposed a suit-

able thin insulator 23, preferably foraminous or formed with perforations placed so at least some of them fall between the lead wires. Examples of such insulators are sintered glass powder, glass cloth or wool, glass beads, mica, a commercial ceramic or refractory, such as that sold under the trade-mark "Aisimag," quartz, etc.

We have found that a preferred insulator is woven glass ribbon $\frac{3}{8}$ " wide and formed from thread .0015" in diameter. All that is needed is a section of such ribbon about $\frac{1}{2}$ " long, which section is held in any suitable manner, as by means of metal strap 24, which is bent around both leads and embraces the insulator 23, as shown in Figures 1, 2 and 3. The metal strap 24 may be formed of degassed nickel, stainless steel, Nichrome, aluminum, nickel-iron alloy, or other similar material.

Although we do not wish to be limited to gas filling, the embodiment of the lamp illustrated is filled with a mixture of 98% argon and 2% nitrogen, by volume, at a pressure of 600 mm. of mercury. After exhausting and filling through the exhaust tube 18, the latter is tipped off as indicated at 25. A conventional type of base 26 is shown cemented to the lamp.

Although we have shown glass cloth 23 held in place by the metal strap 24, which in Figure 3 has its leaves secured together by riveting indicated at 27, yet as an alternative shown in Figure 6, said leaves may be secured together by spot welding 27^a, or as shown in Figure 7 by crimping indicated at 27^b, or in any other suitable manner, as will be understood.

As shown in Figure 8, we propose to employ such lamps in series and energized from a source of current indicated at 28. If the lamp 11^c, for example, fails during operation in series with other lamps 11^d, as by the filament 21^c breaking, an arc occurs through its insulator 23^c and maintains the circuit through the associated lamps 11^d.

From the foregoing, it will be seen that we have devised a lamp with an improved cut-out device which maintains circuit continuity under the intended conditions, covering all lamp failures, even those simultaneously containing air and broken filaments, whereby it is particularly adapted for series service, said device not only giving improved operation as compared with the oxidized aluminum and ceramic holder of the prior art, but involving a reduction in total lamp cost, including saving of about 93% of the cost of such prior art cut-out device.

Although preferred embodiments of our invention have been disclosed, it will be understood that modifications may be made within the spirit and scope of the appended claims.

We claim:

1. An incandescent electric lamp for series service comprising an enclosing translucent vitreous envelope, a mount therein including a pair of leads, a filament supported on the inner end portions thereof, said leads closely paralleling each other for a portion of their lengths inside of said envelope, and a thin layer of foraminous heat-resisting insulating material disposed between said parallel lead portions to maintain a slight spacing thereof, whereby if the filament fails and the total available voltage appears at said leads, an arc occurs therebetween and maintains the circuit.

2. An incandescent electric lamp for series service comprising an enclosing gas-filled glass

envelope, a mount therein including a pair of leads, a filament the ends of which are respectively connected to said leads, the latter closely paralleling one another for a portion of their lengths on the inside of said envelope, and a thin layer of foraminous heat-resisting insulating material disposed between said parallel lead portions to maintain a slight spacing thereof, whereby if the filament fails and the total available voltage appears at said leads, an arc occurs therebetween and maintains the circuit through other lamps if in series therewith.

3. An incandescent electric lamp for series service comprising an enclosing translucent vitreous envelope, a mount therein including a pair of leads, a filament supported on said leads, the latter extending close to one another at one place inside of said envelope, and a thin layer of foraminous heat-resisting insulating material, disposed between said closely-spaced lead portions to maintain the spacing thereof, whereby if the filament fails and the total available voltage appears at said leads, an arc occurs therebetween and maintains the circuit through other lamps if in series therewith.

4. An incandescent electric lamp comprising an enclosing translucent vitreous envelope, a mount therein including a pair of leads, a filament supported on the inner portions thereof, said leads closely paralleling each other for a portion of their lengths inside of said envelope, and a small piece of woven glass ribbon disposed between spacing, and held in place with respect to, said parallel lead portions, whereby if the filament fails and the total available voltage appears at said leads, an arc occurs therebetween and maintains the circuit.

5. An incandescent electric lamp for series service comprising an enclosing gas-filled glass envelope, a mount therein including a pair of leads, a filament supported on said leads, the latter closely paralleling each other for a portion of their lengths inside of said envelope, and a thin layer of foraminous heat-resisting insulating material, disposed between said parallel lead portions to maintain the spacing thereof, whereby if the filament fails and the total available voltage appears at said leads, an arc occurs therebetween and maintains the circuit.

6. An incandescent electric lamp for series service comprising an enclosing gas-filled glass envelope, a mount therein including a pair of leads, a filament the ends of which are respectively connected to said leads, the latter closely paralleling one another for a portion of their lengths on the inside of said envelope, and a small piece of woven glass ribbon disposed between spacing, and held in place with respect to, said parallel lead portions, whereby if the filament fails and the total available voltage appears at said leads, an arc occurs therebetween and maintains the circuit through other lamps if in series therewith.

7. An incandescent electric lamp comprising an enclosing translucent vitreous envelope, a mount therein including a pair of leads, a filament supported on the inner portions thereof, said leads closely paralleling each other for a portion of their lengths inside of said envelope, and a small piece of woven glass ribbon disposed between spacing, and held in place with respect to, said parallel lead portions, by a metal strap embracing it and said leads, whereby if the filament fails and the total available voltage appears at said

leads, an arc occurs therebetween and maintains the circuit.

8. A cut-out device for a series incandescent electric lamp comprising a piece of woven glass ribbon about $\frac{3}{8}$ " wide by $\frac{1}{2}$ " in area and formed from thread about .0015" in diameter, disposed between, spacing, and held in place with respect to parallel lead portions in the envelope of said lamp by a metal strap embracing it and said leads, whereby if the filament of said lamp fails, the total voltage available appears at said leads and an arc occurs therebetween and maintains the circuit through other lamps which may be in series therewith.
